UNITED STATES PATENT OFFICE.

CHARLES EDWARD CORADO, OF WINNIPEG, MANITOBA, CANADA.

HYDROCARBON BURNER.

1,422,930.

Specification of Letters Patent.

Patented July 18, 1922.

Application filed August 19, 1921. Serial No. 493,529.

To all whom it may concern:

Be it known that I, CHARLES EDWARD CORADO, a subject of the King of Great Britain, and resident of the city of Winnipeg, Province of Manitoba, Dominion of Canada, have invented certain new and useful Improvements in Hydrocarbon Burners; and I do hereby declare that the following is a full, clear, and exact description thereof.

10 My invention relates to hydrocarbon burners of the type disclosed in my pending application Serial No. 374,225, and has for its object to provide a burner containing as a component part thereof a combined means for feeding the wick and snuffing or trimming the same, the snuffer being adapted to be moved in a straight line across the top of the wick by a direct thrust from a manually operated member. A further object is

15 to provide a burner in which a more uniform distribution of air to the zone of combustion can be obtained and which may be manufactured at a relatively low cost.

For full comprehension, however, of my invention, reference must be had to the accompanying drawings in which similar reference characters indicate the same parts, and wherein:

Figure 1 is a side elevation of a burner constructed according to my invention;

Figure 2 is a plan view thereof with the cap partly broken away;

Figure 3 is a transverse sectional view taken on line 3—3 Figure 1 and looking in the direction of the arrows; and

Figure 4 is a sectional view taken on line 4—4 Figure 2.

The accompanying drawings illustrate the preferred embodiment of my invention which consists of a burner comprising a body or base 2 and a cap 3. The former consists of a hollow shell containing a chamber 4 and is of reduced diameter and screw-threaded as at 5 for connection with the usual oil font. The side wall 7 of the shell is provided with a circumferential series of spaced openings 8 which are adapted to prevent the accumulation of gas in the chamber 4 and such wall is extended upwardly above the top 9 of the shell as at 10 and provided with a series of air inlet openings 12 which admit air to the space between the cap and the top of the shell. The wick tube which is indicated at 13 extends upwardly through the body to a point at which its top will be positioned a short distance below the high-

est point of the cap. The latter is hinged as at 14 upon the wall 10 and is of the usual dome form having a flame opening 15 in its top and having a circumferential flange 16 at its lower edge which constitutes a gallery for supporting a lamp chimney 17, the gallery, when the cap is down, being adapted to rest upon the upper edge of the wall 10. This upper edge is notched as at 18 to provide additional air inlet openings. The portion of the gallery between the point at which it joins the dome and chimney is provided with a circumferential series of ports 19 which effect communication between the space immediately above the burner body.

In order to provide a more even distribution of air to the zone of combustion the dome of the cap is constituted by a double deck structure the outer deck being indicated at 21 and the inner at 22. The inner deck consists of a pair of deflectors 23 which are located one at each side of the flame opening with their upper ends extending upwardly to a point slightly above the top of the wick tube.

To retain the lamp chimney upon the gallery the latter is provided with a pair of upwardly extending lips 24 and 25 with which a spring clip 26 is adapted to cooperate. The latter is located at a point on the gallery diametrically opposite to the point at which the cap is hinged to the body and such clip also serves to secure the cap upon the body when down. To this end the clip is extended downwardly below the gallery from its point of connection thereof and turned inwardly and upwardly in substantially U form, the upwardly extending arm of the U being of increased width as at 30 for engagement with a stop 31 rigidly mounted upon the wall 10 of the body and the stop is of channel form presenting laterally extending flanges 32 having rounded edges 33. The extreme upper end extends through an opening 34 in a radially extending lug 35 on the gallery and terminates in the clip 26. The means for snuffing the wick in the embodiment illustrated is combined with the means for feeding the same, but to meet certain conditions it may be desirable to have the snuffer operable independently of the wick feeding means. The latter consists of a sprocket shaft 40 extending transversely through the body of the burner and journaled in the side wall thereof and is provided with the usual wick

feeding sprocket 41 the teeth of which are adapted to extend through a slot in the wick tube into engagement with the wick.

The portion of the sprocket shaft which 5 extends through the body of the burner is of round cross-section but that located exteriorly of the burner and which is extended a slight distance from the same is of square cross-section as indicated at 42 and slidably 10 carries a handle 43 of truncated conical form having a cylindrical extension 43^a, and this handle has an axial boring of square cross-section to receive the shaft portion 42 thereby enabling the latter to be turned by 15 the handle and permitting axial movement of the latter thereon. The snuffer proper consists of a rigid strip 44 of substantially inverted U form the lower ends of the arms of which are rigidly connected to the 20 spaced parallel push rods 45 and 46 which are slidably mounted in the wall 10 of the burner and located on opposite sides of the wick tube, the strip being adapted to straddle the latter in its snuffing movement and 25 of a height to just clear the top of the tube.

The push rods are located above and in juxtaposition with the sprocket shaft and their outer ends are connected to the handle 43 whereby axial movement of the handle 30 produces a straight line movement of the strip 44 across the top of the wick tube and between the deflectors 23, the point of connection between the push rods and the handle being effected by offsetting the outer end 35 of the arm 46 to a point alongside the arm 45 and terminating the two rods in a downwardly extending eye 48 which encircles a reduced portion 49 on the cylindrical extension 43^a on the handle. In order to yieldingly maintain the handle in position with 40 the strip 44 located at one side of the wick tube, a helical spring 50 encircles the shaft 40 and bears between the journal and the adjacent end of the handle while the axial 45 movement of the latter away from the burner is limited by a pin 51 rigidly mounted in the outer end of the shaft. To provide a firm grip on the handle it may be knurled as at 52.

50 Although I have described an embodiment employing two push rods, under certain conditions it may be desirable to employ only one.

What I claim is as follows:

55 1. In a hydrocarbon burner the combination with a wick tube; of a wick trimming device consisting of a pair of spaced push rods slidably mounted upon the burner on opposite sides of the wick tube, and a member of substantially inverted U form rigidly 60 connected to said push rods and movable in unison therewith, and across the top of the wick tube, that portion of the member which moves across the top of the wick tube being 65 of narrow width for the purpose of prevent-

ing the flame of the wick being extinguished by such movement.

2. In a hydrocarbon burner the combination with a wick tube; of combined means for feeding the wick and snuffing the same 70 said means consisting of a shaft journaled in the burner, a sprocket mounted upon said shaft and adapted to engage the wick, a snuffing device slidably mounted upon the burner and movable in a straight line across 75 the top of the wick tube, and means for rotating said shaft and for moving said snuffing device across the top of the wick tube.

3. In a hydrocarbon burner the combination with a wick tube; of combined means 80 for feeding the wick and snuffing the same, said means consisting of a shaft journaled in the burner, a sprocket mounted upon said shaft and adapted to engage the wick, a carrier slidably mounted upon said burner, a strip of substantially inverted U form rigidly mounted upon said carrier and movable in unison therewith, said strip being movable across the top of the wick tube, a handle mounted upon said shaft and rotatable in 90 unison therewith and capable of axial movement relatively thereto, said handle being operatively connected to the carrier whereby the strip is moved across the top of the wick tube when the handle is moved axially. 95

4. In a hydrocarbon burner the combination with a wick tube; of combined means for feeding the wick and snuffing the same, said means consisting of a shaft journaled in the burner and extended exteriorly thereof, the extended portion of said shaft being of square cross-section, a pair of push rods slidably mounted in said burner, a strip of substantially inverted U form carried by said push rods and adapted to straddle the top of 100 the wick tube, a handle having a bore of square cross-section adapted to be slidable upon the square portion of said shaft and rotatable in unison therewith, said handle being operatively connected to the push rod 105 whereby the strip is moved across the top of the wick tube when the handle is moved axially, means for yieldingly maintaining the handle in position when the strip is located to one side of the wick tube, said means consisting of a spring encircling said shaft and bearing between the journal and said handle, and means upon said shaft limiting outward movement thereon away from the burner. 115

5. In a hydrocarbon burner the combination with a wick tube; of combined means for feeding the wick and snuffing the same, said means consisting of a shaft journaled in the burner and extended exteriorly thereof, the extended portion being of square 120 cross-section, a unitary member consisting of a pair of spaced push rods journaled on opposite sides of the wick tube and in juxtaposition with the shaft, the outer ends of said push rods terminating in a 125 130

- downwardly extended eye disposed perpendicularly to their length, a handle having a bore of square cross-section and adapted to be slidably fitted upon the square portion of 5 said shaft and having a reduced portion encircled by said eye, a strip of substantially inverted U form carried by said push rods and adapted to be moved across the top of the wick tube when the handle is moved 10 axially, a spring encircling said shaft and bearing between the journal and said handle and adapted to maintain the handle in position with the strip located at one side of the wick tube, and means for limiting axial movement 15 of the handle away from the journal, said means consisting of a pin rigidly carried by said shaft and having its ends protruding therefrom.
6. In a hydrocarbon burner the combination with the body thereof including a wick tube the upper end of which extends above the former and a cap hinged upon said body and being adapted to enclose the upper end 20 of the wick tube, said cap being of double deck structure, the outer deck being of dome form and having a flame opening located above the top of the wick tube and the inner deck presenting a pair of deflectors located 25 on opposite sides of the wick tube adjacent the top thereof, and a snuffing device slidably mounted upon the body of the burner and movable across the top of the wick tube between said deflectors.
7. In a hydrocarbon burner the combination with the body thereof including a wick tube the upper end of which extends above the former and a cap hinged upon said body and being adapted to enclose the upper end 30 of the wick tube, said cap being of double deck structure, the outer deck being of dome form and having a flame opening located above the top of the wick tube and the inner deck presenting a pair of deflectors located 35 on opposite sides of the wick tube adjacent the top thereof, and a snuffing device slidably mounted upon the body of the burner and movable across the top of the wick tube between said deflectors, said device consisting of a pair of push rods slidably mounted in 40 the body of the burner on opposite sides of the wick tube, and a strip of substantially inverted U form rigidly carried by said push rods and movable in unison therewith, said strip being movable across the top of the wick tube and between said deflectors.
8. In a hydrocarbon burner the combination with the body thereof including a wick tube the upper end of which extends above the former and a cap hinged upon said body and being adapted to enclose the upper end 45 of the wick tube, said cap being of double deck structure, the outer deck being of dome form and having a flame opening located above the top of the wick tube and the inner deck presenting a pair of deflectors located 50 on opposite sides of the wick tube adjacent the top thereof, and a snuffing device slidably mounted upon the body of the burner and movable across the top of the wick tube between said deflectors, said device consisting of a pair of push rods slidably mounted in 55 the body of the burner on opposite sides of the wick tube, and a strip of substantially inverted U form rigidly carried by said push rods and movable in unison therewith, said strip being movable across the top of the wick tube and between said deflectors.
9. In a hydrocarbon burner the combination with the body thereof including a wick tube the upper end of which extends above the former and a cap hinged upon said body and being adapted to enclose the upper end 60 of the wick tube, said cap being of double deck structure, the outer deck being of dome form and having a flame opening located above the top of the wick tube and the inner deck presenting a pair of deflectors located 65 on opposite sides of the wick tube adjacent the top thereof, and a snuffing device slidably mounted upon the body of the burner and movable across the top of the wick tube between said deflectors, and means for yieldingly maintaining the strip in position to one side of the wick tube.
10. In a hydrocarbon burner the combination with the body thereof including a wick tube the upper end of which extends above the former and a cap hinged upon said body and being adapted to enclose the upper end 70 of the wick tube, said cap being of double deck structure, the outer deck being of dome form and having a flame opening located above the top of the wick tube and the inner deck presenting a pair of deflectors located 75 on opposite sides of the wick tube adjacent the top thereof, and a snuffing device slidably mounted upon the body of the burner and movable across the top of the wick tube between said deflectors, and means for yieldingly maintaining the strip in position to one side of the wick tube.
11. In a hydrocarbon burner the combination with a wick tube, of combined means for feeding the wick and snuffing the same, said means consisting of a shaft journalled in the burner, a sprocket mounted upon said shaft and adapted to engage the wick, a device 80 slidably mounted upon said shaft and having a portion of inverted U-form movable in a straight line across the top of the wick tube.
12. In a hydrocarbon burner the combination with a wick tube, of combined means for feeding the wick and snuffing the same, said means consisting of a shaft journalled in the burner, a sprocket mounted upon said shaft and adapted to engage the wick, a device 85 slidably mounted upon said shaft and having a portion of inverted U-form movable in a straight line across the top of the wick tube.
13. In a hydrocarbon burner the combination with a wick tube, of combined means for feeding the wick and snuffing the same, said means consisting of a shaft journalled in the burner, a sprocket mounted upon said shaft and adapted to engage the wick, a device 90 slidably mounted upon said shaft and having a portion of inverted U-form movable in a straight line across the top of the wick tube.
14. In a hydrocarbon burner the combination with a wick tube, of combined means for feeding the wick and snuffing the same, said means consisting of a shaft journalled in the burner, a sprocket mounted upon said shaft and adapted to engage the wick, a device 95 slidably mounted upon said shaft and having a portion of inverted U-form movable in a straight line across the top of the wick tube.
15. In a hydrocarbon burner the combination with a wick tube, of combined means for feeding the wick and snuffing the same, said means consisting of a shaft journalled in the burner, a sprocket mounted upon said shaft and adapted to engage the wick, a device 100 slidably mounted upon said shaft and having a portion of inverted U-form movable in a straight line across the top of the wick tube.
16. In a hydrocarbon burner the combination with a wick tube, of combined means for feeding the wick and snuffing the same, said means consisting of a shaft journalled in the burner, a sprocket mounted upon said shaft and adapted to engage the wick, a device 105 slidably mounted upon said shaft and having a portion of inverted U-form movable in a straight line across the top of the wick tube.
17. In a hydrocarbon burner the combination with a wick tube, of combined means for feeding the wick and snuffing the same, said means consisting of a shaft journalled in the burner, a sprocket mounted upon said shaft and adapted to engage the wick, a device 110 slidably mounted upon said shaft and having a portion of inverted U-form movable in a straight line across the top of the wick tube.
18. In a hydrocarbon burner the combination with a wick tube, of combined means for feeding the wick and snuffing the same, said means consisting of a shaft journalled in the burner, a sprocket mounted upon said shaft and adapted to engage the wick, a device 115 slidably mounted upon said shaft and having a portion of inverted U-form movable in a straight line across the top of the wick tube.
19. In a hydrocarbon burner the combination with a wick tube, of combined means for feeding the wick and snuffing the same, said means consisting of a shaft journalled in the burner, a sprocket mounted upon said shaft and adapted to engage the wick, a device 120 slidably mounted upon said shaft and having a portion of inverted U-form movable in a straight line across the top of the wick tube.
20. In a hydrocarbon burner the combination with a wick tube, of combined means for feeding the wick and snuffing the same, said means consisting of a shaft journalled in the burner, a sprocket mounted upon said shaft and adapted to engage the wick, a device 125 slidably mounted upon said shaft and having a portion of inverted U-form movable in a straight line across the top of the wick tube.
21. In a hydrocarbon burner the combination with a wick tube, of combined means for feeding the wick and snuffing the same, 130

said means consisting of a shaft journalled in the burner, a sprocket mounted upon said shaft and adapted to engage the wick, a device slidably mounted upon said shaft and having a portion of reduced width and of inverted U-form movable in a straight line across the top of the wick tube.

In testimony whereof I have signed my name to this specification in the presence of two witnesses.

CHARLES EDWARD CORADO.
